UNITED STATES PATENT OFFICE.

SMITH E. ALLISON, OF CHICAGO, ILLINOIS.

RENOVATOR.

No. 828,916.

Specification of Letters Patent.

Patented Aug. 21, 1906.

Application filed May 2, 1902. Serial No. 105,633.

To all whom it may concern:

Be it known that I, SMITH E. ALLISON, of Chicago, Illinois, have invented certain new and useful Improvements in Renovators, of which the following is a specification.

This invention relates to improvements in renovators, and refers more specifically to renovating apparatus of that type which employs a blast of air for extracting the dust from carpets, cushions, and the like.

The object of the invention is to provide an improved apparatus of the character referred to in which the combined effect of plenum and vacuum pressure is utilized in securing an effective and more cleanly operation; to provide an improved construction of the character above referred to, the blast applying device of which is adapted to be conveniently passed over and applied to the articles to be renovated by hand; to provide an improved construction which operates to effectively prevent the escape of dust which has been loosened by the renovating operation; to provide in an apparatus of this character an improved auxiliary dust-collecting apparatus which serves to effectually precipitate the dust from the blast of air and prevent its escape into the atmosphere; to provide, in connection with an apparatus employing both plenum and exhaust pressure, a visible indicator which indicates to the eye of the operator the relative proportions of plenum and vacuum pressure and to provide, in conjunction therewith, means for regulating these pressures relatively to each other; to provide in an apparatus of the character referred to a completely-closed circuit for the passage of the air through the apparatus whereby the escape of dust is prevented, and, in general, to provide a simple and improved construction of the character referred to.

To the above ends the invention consists in the matters hereinafter described, and more particularly pointed out in the appended claims, and the invention will be more readily understood from the following description by reference to the accompanying drawings, in which—

Figure 1 is a side elevation, with certain parts broken away, of the sweeper proper. Fig. 2 is a bottom plan view of the open base side of the sweeper. Fig. 3 is a side elevation with a part of one side broken away to expose the arrangement of the interior of the dust-collecting device forming an auxiliary feature of the apparatus, and Fig. 4 is a dia-

grammatic view showing the general relations of the several features of the entire apparatus to each other. Fig. 5 is a detail view of a hand-valve.

Referring to said drawings, 1 designates as a whole a chamber which may be of any suitable form and construction and is made substantially open at its lower side, as best indicated in Fig. 2, the said lower or base side being made flat or having its margins arranged to terminate in the same plane, so as to enable it to fit closely to the floor or carpet or other article over which it is passed. Desirably, in order to facilitate its easy movement over the floor or carpet, it is provided with antifriction-rollers 2 at its lower side, which conveniently are situated in inturned extensions or lips 3, which are arranged at the front and rear sides of the base end of the casing and to a limited extent close said base side.

A suitable handle 4 is provided whereby the sweeper may be manipulated, said handle being in the present instance forked or divided at its lower end portion and the two arms thereof arranged to embrace opposite sides in the sweeper-box and pivoted to the latter, as indicated at 5. The handle is also made the means of supporting and in part containing pipe connections through which blast is directed through the sweeper-chamber, as will now be described.

Referring to Figs. 1 and 2, 6 designates a fan-shaped nozzle arranged in the lower part of the sweeper-chamber and provided with a downturned slot-like discharge-opening 7, which extends between and is secured to the side members of the chamber and terminates flush with the lower edges of the latter. With the contracted rear end of said fan-shaped nozzle is suitably connected a pipe-section 8, which extends through an aperture 9 in the rear wall of the sweeper-chamber and with the protruding end of said pipe-section is in turn connected a hose or pipe 10, which in the preferred construction shown herein is extended up through the hollow handle portion 4' of the sweeper-handle 4. At the upper end of the sweeper-handle the pipe 10 connects with a valve member, (designated as a whole 11,) and which may be of a well-understood construction, such as is used for pneumatic hammers and the like for controlling the flow of air to and through the pipe 10; a manually-operable valve-lever 12, forming a part of the throttling mechan-

ism and operating a valve-piece 12', movably mounted in the passage 12'', as shown clearly in Figs. 1 and 5. With the end of the valve member 11 opposite that connected with the handle and the pipe 10 is connected a supply-pipe 13, which leads to and is connected with the equalizing-chamber 14 of the air-pump mechanism shown in Fig. 4. The upper side of the sweeper chamber or box is desirably of upwardly-tapering construction, terminating in a neck-like extension 15, with which is connected an exhaust mechanism, comprising a soft rubber or analogous bulb 16 and an eduction-pipe leading from the upper side of the bulb to and extending through the hollow portion of the handle of the sweeper, similarly to the arrangement of pipe 10, the end of the pipe 17 being connected at the upper end of the handle with an extension pipe or hose 18, which leads to and is connected with a precipitating-chamber, (designated as a whole 19 and shown in detail in Fig. 3.) The bulb 16 is preferably detachably connected with the top of the sweeper-box in any suitable manner—as, for example, by being provided with a terminal nipple 20, which fits upon the corresponding neck 15 of the sweeper-chamber. The bulb 16 is constructed of elastic rubber, which tends to retain its normal form and requires a definite amount of internal pressure to expand it or an exhaust-pressure to collapse it, so that it alternately expands and contracts as the pressure of the air flowing therethrough increases or decreases. The bulb, therefore, serves the function of a visible signal to the operator by which he is enabled to determine with sufficient accuracy the relation of the vacuum to the plenum pressure.

The preferred construction of the precipitating or dust-collecting chamber illustrated herein is as follows: The chamber 19 is of rectangular form and suitably constructed to form a sealed inclosure, the lower part being filled with water when in use, as indicated at 21. The inleading pipe 18 enters through the central part of the top side, as indicated at 22, and extends downwardly to a point near the bottom of the chamber and below the liquid-level therein. From the upper portion of the chamber an eduction-pipe 23 leads to and is connected with the pressure-chamber 14 of the air-pump, hereinbefore referred to. By means of the hereinbefore-described connections the exhaust-pressure induced through the pipe 23 causes the blast of air from the sweeper-chamber to flow into the precipitating-chamber, the air as it escapes from the inleading pipe 18 passing up through the body of liquid 21, and thus being washed and caused to precipitate the dust with which it is laden.

It will be obvious from the foregoing that the body of liquid contained in the chamber 19 will rapidly become charged with dust and

sludge, so that it is necessary to renew the liquid from time to time, and it is also necessary or desirable to flush out the entire interior of the precipitating-chamber for the reason that the dust tends to adhere to the sides in the form of a sticky shine. In order to provide for the renewal of the liquid and the flushing of the chamber, I provide an inlet-pipe 24, which desirably enters at one of the angles of the chamber and terminates closely within said angle in a rose 25 or spraying device having divergent outlets 26 and 27, which respectively flush the contiguous sides of the chamber. A central outlet 28 is designed to spray the entering liquid over the remaining interior surface of the chamber. The liquid will, it is to be understood, be admitted under pressure, and in order that the supply may be controlled and shut off at will I provide a controlling-cock 29 in the inlet-pipe 24. An eduction-pipe 30 is arranged to lead out from the chamber at a point near the bottom thereof, as indicated clearly in Fig. 3, which eduction-pipe is likewise provided with the controlling-cock 31.

In the use of the sweeper it is obvious that more or less dirt and debris will be dislodged which is too heavy and too large to be drawn off through the exhaust-pipes, but will, nevertheless, be picked up by the incoming blast of air. In order to collect such dirt, I provide in the lower part of the sweeper-chamber a horizontal pan 32, which desirably extends across the full width of the chamber from side to side, but is somewhat narrower from front to rear than the interior of the chamber and is provided with relatively narrow upstanding sides at its front and rear edges, as indicated at 33. Between the upturned sides 33 and the proximate walls of the chamber are formed blast-passages 34, which passages, in conjunction with the tapering top of the chamber, serve to deflect the heavier pieces of dirt and the like inwardly toward the center of the chamber and above the pan 32.

Any suitable mechanism may be employed in supplying the pressure-chamber 14—such, for example, as an ordinary air-pump, which is shown diagrammatically at 35 in Fig. 4—and in this connection it may be stated that while the arrangement shown herein is preferable and produces certain advantages peculiar thereto, yet, nevertheless, it is not essential that the plenum-pressure pipe and the exhaust-pipe be both connected with a common pressure-chamber or with a common draft-inducing machine. However, as hereinbefore intimated, the arrangement shown herein, in which a completely-closed circulation is provided for, is most advantageous, for the reason that it prevents the escape of any dust or dirt from the system, and for the further reason that when a closed circuit apparatus is used it is easier to regu-

late the relation of the plenum-pressure to the exhaust-pressure, so as to insure at all times a tendency to draw external air into the suction side of the system.

- 5 The operation of an apparatus constructed and arranged as described is probably entirely obvious from the foregoing description, but may be briefly summarized as follows: Assuming, for example, that it is desired to renovate the carpets of a room outlined in the diagrammatic view Fig. 4 at 36, the air-pump, pressure-chamber, and precipitating or filtering chamber, together constituting the operating plant, are placed along 10 side of the house and the pipes passed in through one of the openings and connected with the sweeper within the room. The connection with the sweeper having been made, the pump is started and a powerful circulation of air induced through the sweeper, the blast or air under pressure passing in through the pipe 13 10 escaping from the downwardly-directed nozzle and impinging against the carpet upon which the sweeper 15 rests. At the same time the exhaust action draws upwardly the air discharged through the nozzle against the carpet, so that the air charged with dust and dirt dislodged by the blast is drawn upwardly and out through the 20 eduction-pipe. Those pieces of dirt and debris which are too large to float with the outgoing current of air are dislodged and lifted to a certain extent by the force of the jet of air issuing from the nozzle, but as soon as 25 they pass out of the immediate influence of the jet fall backwardly by their weight and lodge within the gathering-pan. The operator passes the device more or less slowly over the entire area of carpet and meantime regulates the flow of air through the pressure side 30 by means of the valve mechanism 11, so that it does not exceed the exhaust action or outflow of air through the eduction side. The operator is enabled to readily accomplish this by simply keeping watch of the expandable bulb 16, which expands as the plenum side pressure increases and contracts as the 35 vacuum or exhaust pressure is augmented. The exhaust action of the pump acting through the eduction-pipe 23 of the precipitating-chamber induces the flow of air inwardly through the pipe 18 and causes the dust-laden blast to rise through the body of liquid contained in the precipitating-chamber, thus drenching the blast of air and freeing 40 it of the dust and dirt, the purified air passing on through the pipe 23 into the cylinder of the pump and thence again through the system. From time to time as the liquid 45 in the precipitating-chamber becomes muddy to such an extent as to prevent its proper cleansing action the chamber is flushed out in the manner hereinbefore described, and by reason of the peculiar arrangement of the inlet and outlet supply pipes this operation of 50

renewing the supply of liquid may be, if preferred, accomplished without interrupting the renovating operation of the apparatus.

It will be understood from the foregoing that there is no tendency of the dust-laden air to escape from any part of the system; but, on the contrary, if the exhaust action of the blast-inducing apparatus be properly controlled there will always be a slight tendency of the outer atmosphere to flow into the exhaust side of the system, thus insuring that the dust and dirt dislodged by the sweeper shall not escape into the surrounding atmosphere. Furthermore, by employing the precipitating apparatus described herein the dust is not discharged into the outer atmosphere, and the disagreeable and unhealthy conditions incident to such method are obviated.

It will be understood from the foregoing description that an apparatus embodying my invention is capable of effectively cleaning or renovating carpets, cushions, and the like without necessitating the removal of the same from their normal positions, since the sweeper may be conveniently passed over a carpet or rug or seat-cushion or the like, it being only necessary that the base side of the sweeper-chamber should fit with approximate accuracy against the surface over which it is passing in order to insure effective operation. It will be further obvious that the details of construction may be modified without in any sense departing from the spirit of the invention, and I do not, therefore, limit myself to the details of construction shown herein, except to the extent that the same are made the subject of specific claims.

I claim as my invention—

1. In a renovating apparatus, the combination with a sweeper-chamber provided at its base side with an opening, of a blast-nozzle arranged to discharge within said sweeper-chamber and directed toward said opening, a supply-pipe connected with said nozzle, an eduction-pipe connected with the sweeper-chamber at a point above the lower side thereof, means for inducing a simultaneous circulation through said supply and eduction pipes, a manually-operable controlling-valve connected with said supply-pipe, and a visible signal for indicating the regulation of said valve connected in circuit with the supply and exhaust sides of the apparatus, for the purpose set forth.

2. In an air-blast renovating apparatus, the combination with a sweeper-chamber provided at one side with an opening through which the surface to be renovated may be subjected to a blast, a nozzle discharging within said sweeper-chamber and directed against the surface exposed through said opening, a supply-pipe connected with said nozzle, an exhaust-pipe leading from said sweeper-chamber, a precipitating-chamber

- into which said exhaust-pipe discharges, an elastic bulb interposed in said exhaust-pipe between said sweeper-chamber and said precipitating-chamber, and means connecting said precipitating-chamber with said supply-pipe and forming a complete circuit, said means being adapted to produce a circulation of air through said circuit for the purposes described.
10. 3. An air-blast sweeper comprising a chamber provided at its base side with an opening, a blast-nozzle having a relatively long and narrow discharge-outlet arranged to extend transversely of such chamber, a collecting-pan arranged horizontally at a distance above the bottom of the chamber and forming in conjunction with the sides of the latter a partition which partially divides the sweeper-chamber and provides relatively narrow transversely-extending air-passages at each end of said pan, an outlet-passage leading from said sweeper-chamber centrally above the pan, and supply and exhaust pipes connected with said nozzle and outlet-passage respectively.
15. 4. An air-blast sweeper comprising a chamber provided at its base side with an opening, a blast-nozzle having a relatively long and narrow discharge-outlet arranged to extend transversely of such chamber, a collecting-pan arranged horizontally at a dis-

tance above the bottom of the chamber and forming in conjunction with the sides of the latter a partition which partially divides the sweeper-chamber and provides relatively narrow transversely-extending air-passages at each end of said pan, an outlet-passage leading from said sweeper-chamber centrally above the pan, and supply and exhaust pipes connected with said nozzle and outlet-passage respectively, the top wall of said sweeper-chamber being constructed to taper upwardly and to converge to the discharge-outlet of the sweeper-chamber, substantially as described.

5. In a renovating apparatus, the combination with an air-blast sweeper, of supply and exhaust pipes connected with said sweeper, a dust-precipitating chamber into which said exhaust-pipe discharges, a visible signal for indicating pressure comprising an elastic air-bulb interposed in said exhaust-pipe and adapted to collapse or expand as the pressure of the air flowing therethrough decreases or increases, and an air-pump for supplying air to said supply-pipe and creating an exhaust-pressure in said exhaust-pipe, substantially as described.

SMITH E. ALLISON.
